METHOD OF PREPARING OIL-SOLUBLE SULFONATES

Norman E. Lemmon, Hammond, Ind., assignor to
Standard Oil Company, Chicago, Ill., a corpora-
tion of Indiana

Application December 22, 1944, Serial No. 569,410

6 Claims. (Cl. 260—505)

1

This invention relates to improvements in the method of preparing preferentially oil-soluble sulfonic acids and sulfonates and more particularly relates to an improved process for the preparation of synthetic preferentially oil-soluble sulfonic acids and sulfonates resulting from the sulfonation of alkylated aromatic hydrocarbons.

Sulfonated alkyl aromatic hydrocarbons have been widely used as wetting, washing, emulsifying and detergent agents. Depending upon the length of the alkyl chain of the alkyl substituent, the sulfonated alkyl aromatic hydrocarbons are either preferentially water-soluble or preferentially oil-soluble. For example, alkyl benzene sulfonates in which the alkyl group contains from about 10 to about 15 carbon atoms are preferentially water-soluble and are useful as wetting and/or detergent agents. The higher alkyl benzene sulfonates, that is, alkyl benzene sulfonates containing more than 16 carbon atoms and usually from about 18 to about 30 carbon atoms in the alkyl groups, are preferentially oil-soluble. These preferentially oil-soluble alkyl aromatic sulfonates in many respects resemble the preferentially oil-soluble sulfonates obtained in the treatment of petroleum oils with concentrated or fuming sulfuric acid. These preferentially oil-soluble petroleum sulfonates, because of their characteristic color are generally referred to as mahogany soaps although certain preferentially oil-soluble petroleum sulfonates having a characteristic brownish color are called brown acid soaps.

The alkylated aromatics containing from about 10 to about 15 carbon atoms in the alkyl chain are selectively sulfonated with from about 88% to about 98% sulfuric acid. The sulfonates so obtained are of the preferentially water-soluble type and are separated from the unreacted higher alkylated aromatics by stratification or other suitable means. Heretofore the higher alkylated aromatics have been sulfonated to obtain preferentially oil-soluble sulfonates by treatment with sulfuric acid of from about 98% to about 104½% strength. Large treating losses are obtained by this process since it is extremely difficult to separate the spent acid from the sulfonated higher alkylated aromatics. In addition to the large treating losses, it is difficult to obtain a purified sulfonate having a low inorganic salt content.

It is an object of this invention to provide an improved method of preparing preferentially oil-soluble alkylated aromatic sulfonic acids and

2

sulfonates. Another object of the invention is to provide an improved method of obtaining low inorganic salt content, preferentially oil-soluble alkylated aromatic sulfonic acids and sulfonates having more than 17 carbon atoms in the alkyl chain. Another object of my invention is to provide an improved method of sulfonating alkyl aromatics having more than 17 carbon atoms in the alkyl chain whereby a product having a low inorganic salt content is obtained. Other objects and advantages of the present invention will become apparent from the following description thereof, read in conjunction with the accompanying drawing, which is a schematic flow diagram of a preferred method of carrying out the invention, and which forms a part of this specification.

In accordance with the present invention alkylated aromatic hydrocarbons having at least 18 carbon atoms in the alkyl chains and preferably from about 18 to 30 or more carbon atoms in the alkyl chains, are sulfonated by reaction with sulfur trioxide at a temperature of from about 50° F. to about 200° F. and preferably from about 75° F. to about 175° F. in an atmosphere of nitrogen or air for a period sufficient to permit substantially complete sulfonation of the alkylated aromatic. Depending upon the temperature employed, the reaction period can range from about 5 minutes to about 60 minutes or more. By employing sulfur trioxide as the sulfonating agent in place of the usual concentrated or fuming sulfuric acid, the resultant preferentially oil-soluble sulfonic acids or sulfonates are substantially free of contamination with sulfuric acid. The small amount of sulfuric acid resulting from the reaction of water and SO₃ which may be occluded in the sulfonate can be readily removed by contacting the sulfonic acids with clay, as more fully hereinafter described.

The present invention can be applied to a wide variety of alkyl aromatic compounds in which the alkyl substituent has at least 18 carbon atoms in the chain. The aromatic nucleus can be, for example, benzene, toluene, xylene, cumene, naphthalene, methyl naphthalenes, ethyl naphthalenes, isopropyl or alkyl naphthalenes, diphenyl, alkyl phenyls, anthracene, and alkyl anthracene. Halogen, nitro, hydroxy or other derivatives of the aromatic hydrocarbons can also be sulfonated in accordance with the present invention.

The aromatic nucleus may be alkylated to produce alkylated aromatics having at least 18 carbon atoms in the alkyl chain or the aromatic

nucleus may be alkylated with a mixture of alkylating agents wherein the length of the alkyl group can vary from those having less than 18 carbon atoms and those having at least 18 carbon atoms. When the alkylated aromatic compound contains mixtures of alkyl substituents in which the length of the alkyl group varies from those having less than 18 carbon atoms and those having at least 18 carbon atoms, alkymers having at least 18 carbon atoms can be segregated from such mixture by several suitable means. For example, the mixture of alkymers may be subjected to fractional distillation to obtain a suitable material having at least 18 carbon atoms in the alkyl chain or the mixture of alkymers may be selectively sulfonated as hereinafter-described. The alkylating agents may be haloparaffins, olefins, olefin polymers, alkyl sulfates, aliphatic alcohols or aliphatic esters of wide molecular weight range.

The alkylation of the aromatic compound by alkylating agents of the foregoing type can be accomplished by reacting the aromatic and the alkylating agent in the presence of 90% to 100% sulfuric acid, aluminum chloride, preferably activated with a trace of hydrogen chloride, hydrogen fluoride, boron fluoride, mixtures of hydrogen fluoride and boron fluoride or other known alkylation catalysts.

Suitable alkylating agents are olefin polymers, particularly those of ethylene, propylene, butylenes, amylenes and the like or mixtures thereof, preferably those having at least about 18 carbon atoms in the chain and preferably from about 18 to about 30 carbon atoms in the alkyl chain. Suitable olefin polymers are those having a distillation range of from about 220° F. to about 500° F. at 5 mm. Propylene polymers and butylene polymers of at least about 18 carbon atoms are especially suitable as alkylating agents for the aromatic hydrocarbons. Butylene and propylene polymers having an initial boiling point of at least about 230° F. at 5 mm. are especially well adapted for the alkylation of the aromatic hydrocarbons. Propylene can be polymerized by passing it in the liquid phase through a pool of dispersed aluminum chloride catalyst to yield a polymer of relatively wide boiling and molecular weight ranges. While the total polymer may be employed in the alkylation of the aromatic hydrocarbon, it is preferred to fractionate the polymer to remove a fraction boiling below about 230° F. at 5 mm. and corresponding to polymers of less than 18 carbon atoms. The residuum comprising polymers boiling above about 230° F. at 5 mm. and of at least 18 carbon atoms can then be used as the alkylating agent in the alkylation of a desired aromatic compound, for example benzene, toluene and the like. These higher alkymers are then sulfonated with sulfur trioxide in the manner hereinafter-described.

Alternatively the aromatic compound can be alkylated with the total polymer and the alkymers selectively sulfonated by treatment with sulfuric acid of from about 88 to 98 weight percent strength at a temperature in the approximate range of from about 50° F. to about 150° F. The initial sulfuric acid strength and other reaction conditions are adjusted and selected to effect the selective sulfonation only of those alkyl aromatics whose monosulfonic acids are preferentially water-soluble. From about 0.2 to about 2 volumes of acid per volume of alkylated aromatic are suitably employed and the reaction time can vary from about 1 to about 20 hours or more de-

pending upon the nature of the specific feed stock, acid strength and other reaction conditions. The selective sulfonation depends upon the proper strength and amount of sulfuric acid. For example, in the sulfonation of alkyl benzenes it is essential that the acid strength be such that only alkyl benzenes containing less than about 18 carbon atoms in the alkyl group are sulfonated. It is likewise important that the amount of acid be sufficient so that the spent acid is of sufficient strength to retain in solution the alkyl benzene sulfonic acid containing less than about 9 carbon atoms in the alkyl group. After completion of the selective sulfonation the reaction products can be separated by a variety of methods such as, for example, by solvent extraction, dilution with water and stratification. It is preferable, however, to allow the reaction mixture to stratify without the addition of water or other diluting media. Generally three strata are obtained, the lowest stratum comprising essentially spent sulfuric acid and alkyl aromatic sulfonic acids in which the alkyl group contains less than 9 carbon atoms. The middle stratum comprises predominantly the alkyl aromatic sulfonic acids of from about 9 to about 17 carbon atoms in the alkyl group which are preferentially water-soluble. The upper stratum comprises predominantly unsulfonated alkyl aromatics in which the alkyl groups contain at least 18 carbon atoms. Upon segregation of the various strata, the upper stratum constitutes the starting material for the sulfonation of preferentially oil-soluble sulfonic acid compounds prepared as hereinafter-described.

As mentioned above, the present invention is applicable to the sulfonation of higher alkylated aromatics in which the alkylation is brought about by means of alkylating agents other than olefin polymers. For example, the non-aromatic hydrocarbons may be converted to suitable alkylation form in various ways. For example halogenated paraffin hydrocarbons having the proper distillation characteristics can be employed in the manner described in U. S. Patent 2,233,408 issued to L. H. Flett on March 4, 1941.

The present invention will be clearly understood from the following description thereof read in conjunction with the accompanying drawing. Referring to the drawing, olefin polymers such as butylene polymers or propylene polymers of from about 9 to about 30 or more carbon atoms are introduced from a storage tank 1 through line 2 to an alkylation zone 3. Anhydrous HCl and an aromatic hydrocarbon such as toluene are introduced into alkylation zone 3 through a line 4. Alkylation of the aromatic takes place in the alkylation zone 3 at a temperature of about 80° F. Light ends are removed from the alkylation zone 3 and removed overhead through a line 5 and an aluminum complex is withdrawn from the zone 3 through a line 6. The alkylated aromatics hereinafter referred to as the alkymers are withdrawn from the alkylation zone 3 through a line 7 and introduced into a reactor 8 wherein it is treated with sulfuric acid of from about 88% to about 98% strength, introduced through a line 9 and the alkymers having from about 9 to about 17 carbon atoms in the alkyl groups selectively sulfonated. After this selective sulfonation the reaction mixture is permitted to stratify into a lower layer comprising essentially spent sulfuric acid and alkyl aromatic sulfonic acids having less than 9 carbon atoms in the alkyl group, which are withdrawn from the reactor 8

through a line 16; a middle layer comprising predominantly sulfonated alkymers having from about 9 to about 17 carbon atoms in the alkyl group which are withdrawn from the reactor 8 through a line 11; and an upper layer comprising predominantly unsulfonated alkymers in which the alkyl groups contain more than about 17 carbon atoms. This upper layer is withdrawn from the reactor 8 through a line 12 and introduced into a reactor 13 wherein it is sulfonated by treatment with SO_3 introduced through a line 14. Preferably the sulfonation in reactor 13 takes place in an atmosphere of nitrogen or air introduced through a line 15. Sulfonation of the alkymers in reactor 13 is carried out at a temperature of from about 50° F. to about 200° F. and preferably at a temperature of about 175° F. Upon completion of the sulfonation reaction the sulfonic acids formed are blown free of SO_2 and unreacted SO_3 by blowing with air or nitrogen introduced through line 16, the gases being removed from the reactor through vent 17. The sulfonic acids substantially free of SO_2 and unreacted SO_3 but containing a small amount of sulfuric acid resulting from the reaction of SO_3 and water of reaction are withdrawn from reactor 13 through line 18 to mixer 19 wherein it is diluted with about an equal volume of a light hydrocarbon oil such as naphtha or a treated oil introduced into mixer 19 through line 20. The oil diluted sulfonic acids are then passed through line 21 to contactor 22 wherein they are contacted with from about 1% to about 3% of an adsorption clay at a temperature of from about 100° F. to about 200° F. to substantially completely remove the sulfuric acid contained in the sulfonic acids. The mixture of sulfonic acids and clay is then passed through line 23 to a filter press 24 to remove the clay, and the filtrate of oil diluted sulfonic acids substantially free of sulfuric acids withdrawn from the filter 24 through line 25 and introduced into a reactor 26 wherein it is neutralized with caustic soda introduced into the reactor 26 through line 27. After the neutralization is completed water is removed from reactor 26 through line 28, the neutralized product brightened by air blowing, and the oil solution of sodium sulfonates having a low salt content removed through line 29 to suitable storage (not shown).

The present invention may be clearly understood from the following specific example which is given by way of illustration only and is not intended to be considered as a limitation of the invention. An alkylated benzene obtained by alkylating benzene with a propylene polymer having a distillation range of from about 100° F. to about 430° F. at 5 mm. and comprising substantially a mixture of C_9 to C_{30} , or more aliphatic hydrocarbons was sulfonated by treatment with 96% sulfuric acid at a temperature of about 80° F. for about 10 hours. The sulfonic acids resulting from this sulfonation step comprised essentially of preferentially water-soluble alkyl aromatic sulfonic acids having less than about 18 carbon atoms in the alkyl chain, were separated from the unsulfonated portion by decantation. The unsulfonated higher alkylated benzene was washed with alcohol and then treated with sulfur trioxide at a temperature of 175° F. for 30 minutes in an atmosphere of nitrogen. The product obtained comprised essentially higher alkylated benzene sulfonic acids which were preferentially oil-soluble and which contained only a very small amount of sulfuric acid

resulting from the reaction of SO_3 and water. This product was diluted with an equal volume of a refined white oil and contacted with 1% of an adsorbent clay. The product was then filtered, carefully neutralized with sodium hydroxide and the water removed therefrom by distillation.

The following data represent the yield and the weight balance based on the higher alkylmer used, obtained in the above example:

	Grams
Weight of alkylmer charged	100
Weight of alkylmer sulfonated	69.89
Weight of alkylmer sulfonate recovered	85.89
Weight of alkylmer lost	7.7
Weight of alkylmer lost after neutralization	22.6
Weight of SO_3 added	26.8
Weight of SO_3 converted to sulfonate	16.0

The apparent high loss after neutralization was due to the presence of some low boiling materials in the alkylmer which were evaporated off on removal of water from the recovered sulfonate. The sulfonate recovered showed the following analysis based on a 1:1 dilution with white oil:

	Per cent
Oil	48.9
Soap	43.4
Salts	2.9

The salt content of preferentially oil-soluble sulfonates obtained by treating alkylated aromatics with 18 or more carbon atoms in the alkyl groups in the conventional manner, that is, with fuming sulfuric acid, is generally of the order of magnitude of about 10% or even greater. Such a product would need to be desalts and considerable loss of soap would result in this operation.

While I have described my invention by reference to specific embodiments thereof, the invention is not intended to be limited thereto but includes within its scope such modifications as come within the spirit of the appended claims.

I claim:

1. The method of preparing a preferentially oil-soluble alkylated aromatic sulfonate comprising sulfonating an alkylated aromatic hydrocarbon having at least 18 carbon atoms in the alkyl group with sulfur trioxide, blowing the sulfonated alkylated aromatic hydrocarbon with a gas to remove SO_2 and SO_3 , contacting the blown alkylated aromatic sulfonic acid with a small amount of an adsorption clay, whereby an alkylated aromatic sulfonic acid substantially free of sulfuric acid is obtained, and neutralizing said clay-contacted alkylated aromatic sulfonic acid whereby a preferentially oil-soluble alkylated aromatic sulfonate having a relatively low inorganic sulfate content is obtained.

2. The method of preparing a preferentially oil-soluble alkylated aromatic sulfonate comprising treating an alkylated aromatic hydrocarbon containing at least 18 carbon atoms in the alkyl group with sulfur trioxide, blowing the alkylated aromatic sulfonic acid formed to remove SO_2 and SO_3 , diluting the blown alkylated aromatic sulfonic acid with a hydrocarbon oil, contacting the diluted blown alkylated aromatic sulfonic acid with an adsorption clay, and neutralizing said clay-contacted oil solution of alkylated aromatic sulfonic acid whereby a preferentially oil-soluble alkylated aromatic sulfonate substantially free of inorganic sulfates is obtained.

3. The method of preparing a preferentially oil-soluble polyolefin alkylated benzene sulfonate

comprising treating a polyolefin alkylated benzene containing at least 18 carbon atoms in the alkyl group with sulfur trioxide, blowing the resultant polyolefin alkylated benzene sulfonic acid to remove SO_2 and SO_3 , diluting the blown polyolefin alkylated benzene sulfonic acid with a hydrocarbon oil, diluting said diluted sulfonic acid with an adsorption clay, separating the diluted sulfonic acid from said adsorption clay and neutralizing the clay-contacted oil solution of said polyolefin alkylated benzene sulfonic acid, whereby a preferentially oil-soluble polyolefin alkylated benzene sulfonate substantially free of inorganic sulfates is obtained.

4. The method of preparing preferentially oil-soluble alkylated aromatic sulfonates comprising sulfonating alkylated aromatic hydrocarbons containing more than 18 carbon atoms in the alkyl group with sulfur trioxide at a temperature of from about 50° F. to about 200° F., blowing the resultant alkylated aromatic sulfonic acids to remove SO_2 and SO_3 therefrom, diluting the blown alkylated aromatic sulfonic acids with a hydrocarbon oil, contacting the oil solution of alkylated aromatic sulfonic acids with an adsorption clay at a temperature of about 100° to 200° F., separating the clay from the alkylated aromatic sulfonic acids and neutralizing the clay-contacted alkylated aromatic sulfonic acids with caustic, whereby preferentially oil-soluble alkylated aromatic sulfonates substantially free of inorganic sulfates are obtained.

5. The method of claim 4, in which the diluted blown alkylated aromatic sulfonic acids are contacted with from about 1% to about 3% of an adsorption clay.

6. The method of preparing a preferentially oil-soluble alkylated aromatic sulfonate comprising treating an alkylated aromatic hydrocarbon having at least 18 carbon atoms in the alkyl group with sulfur trioxide, blowing the resultant alkylated aromatic sulfonic acid to remove SO_2 and SO_3 therefrom, and neutralizing the blown alkylated aromatic sulfonic acid to obtain an alkylated aromatic sulfonate having a relatively low inorganic sulfate content.
